HOLDER

Arthur P. Jorgenson, Racine, Wis., assignor to
 Landon P. Smith, Inc., Irvington, N. J., a corporation of New Jersey

Application May 24, 1938, Serial No. 209,671

1 Claim. (Cl. 279—112)

My invention relates to improvements in holders of the type more particularly adapted for use in connection with paint-mixing apparatus of the general type disclosed in my Patent No. 2,109,233, issued February 22, 1938.

One of the objects of my invention is the provision of a holder of the character referred to which is relatively simple in construction and manner of operation, which can be easily and quickly applied to the driving apparatus therefore, and which is capable of holding the cans of paint securely for the vigorous, compound motion imparted to them by the driving apparatus.

Other objects and advantages will hereinafter appear.

For the purpose of illustrating my invention, an embodiment thereof is shown in the drawing, in which

Figure 1 is an elevational view, partly in section, 20 of a holder constructed and operating in accordance with my invention, the section being taken on the line 1—1 in Fig. 3;

Fig. 2 is a sectional view taken on the line 2—2 in Fig. 1;

Fig. 3 is a plan view of Fig. 1; and

Fig. 4 is a detail view partly in section, the section being taken on the line 4—4 in Fig. 1.

With reference to the drawing, my improved holder comprises a member 10 provided centrally thereof with a socket 11 for receiving the free end of a shaft 12 and at each end thereof with an enlarged boss 13 disposed with its axis 14 perpendicular to the axis of the socket. The socket is split on both sides thereof, as shown more clearly in Fig. 2.

Pins 16 extend respectively through and are fixed in the bosses 13.

Complementary jaws 17 are slideable on the pins 16.

40 A right-and-left-thread adjusting screw 18 engages the jaws 17, as shown, and passes through the socket 11.

The screw 18 is provided centrally thereof with a recess 19, and the end of the shaft 12 is recessed to fit the screw at the recess 19 whereby it is held against axial movement relatively with respect to the member 10.

A locking element or nut 20 is disposed in the socket 11 and engages the screw 18 at the recess 19 to hold it in its position of adjustment and against axial movement relatively with respect to the member 10.

In applying the holder to the free end of shaft 12, the locking element 20 is first inserted into the socket 11 and the screw 18 then passed through the opening 21 in the socket, this opening being made sufficiently large to allow clearance for this purpose.

The holder is forced onto the free end of the shaft 12, and held in place by bolts 22, with the screw 18 gripped between the locking element 20 and the adjacent end of shaft 12 sufficiently tight to hold the screw in its position of adjustment, while still permitting turning of the screw by using a wrench.

In operation, the can 23 of paint is placed between the jaws 17, and the screw 18 turned to 15 grip the can securely between the jaws.

The driving apparatus is described in my Patent No. 2,109,233, and operates to impart a vigorous rocking movement to the shaft 12 and, simultaneously, to impart a vigorous reciprocating movement to the shaft along its axis. By reason of this vigorous, compound movement, the contents of the can are thoroughly and uniformly mixed in a few minutes.

The adjacent faces of the jaws 17 may be 25 stepped as shown in Fig. 1, to accommodate cans of different sizes.

It will be understood that various modifications within the conception of those skilled in the art may be made without departing from the 30 spirit of my invention or the scope of the claim.

I claim as my invention:

In a holder of the character described having a member provided centrally thereof with a socket for receiving the free end of a shaft, pins 35 carried by said member and disposed respectively on opposite sides of said socket, complementary jaws slideable on said pins, and a right-and-left-thread adjusting screw engaging said jaws and passing through said socket; means for holding 40 said screw in said socket comprising a substantially central recess in said screw adapted to receive the free end of said shaft, and a locking element disposed in said socket on the opposite side from said shaft end whereby said screw is 45 gripped between said element and the adjacent end of said shaft sufficiently tight to hold said screw in its position of adjustment while still providing for manual turning of the screw.

50

ARTHUR P. JORGENSEN.
